SELF-OPENING AND CLOSING CAP FOR
COLLAPSIBLE TUBES

Gaston L. Lateur, San Francisco, Calif.

Application November 18, 1935, Serial No. 50,417

9 Claims. (Cl. 221—60)

My invention relates to improvements in self-opening and closing caps for collapsible tubes, and it consists of the combinations, constructions and arrangements hereinafter described 5 and claimed.

An object of my invention is to provide an improvement over the form of the device shown in my co-pending application, Serial No. 38,834 filed August 31, 1935. In the co-pending application I show a cap provided with a tongue and a spring-pressed piston for yieldingly holding the tongue in closed position to cover an outlet opening in the cap. When the tube is squeezed the material therein will force the piston away 10 from the opening in the end of the cap and the piston in turn will carry the tongue away from the opening with the result that the material will be forced through the opening. When the pressure on the tube is released the spring-pressed piston exerts sufficient force to again cause the 15 tongue to close the opening.

In the present invention the spring-pressed piston instead of moving away from the open end of the cap when the tube is squeezed, will move 20 toward this end. In other words, the movement is reversed and the piston carries an outlet mouth and when the piston is moved toward the end of the cap by the pressure of the material, this mouth will project beyond the opening in 25 the cap and will permit the material to flow out from the device. The spring-pressed piston will exert sufficient force to retract the mouth and close the opening in the cap when the pressure on the tube is released.

30 I further show a novel locking feature for positively preventing the tube from being accidentally opened from the time the tube leaves the manufacturer to the time the device is actually purchased. The mouth of the device is so arranged 35 to cause the material to be ejected in a ribbon-like form, and this will aid the spreading of the material on a tooth brush should the device contain tooth paste.

The device is extremely simple in construction 40 and is durable and efficient for the purpose intended.

Other objects and advantages will appear in the following specification, and the novel features of the device will be particularly pointed 45 out in the appended claims.

50 My invention is illustrated in the accompanying drawing forming a part of this application, in which

Figure 1 is a vertical section through the device 55 shown operatively applied to a collapsible tube;

Figure 2 is a view somewhat similar to Figure 1, but shows the mouth of the device in open position;

Figure 3 is an isometric view of the mouth and piston;

Figure 4 is a sectional view of a slightly modified form of the invention; and

Figure 5 shows a locking device used in connection with the form of the device shown in Figure 4.

In carrying out my invention I make use of a collapsible tube indicated generally at 1, this tube having the customary exteriorly threaded neck portion 2. A cap 3 is threaded upon the neck 2 and has a V-shaped or conical-shaped 15 top 4 provided with an inwardly extending cylindrical portion 5. The cap has an opening 6 therein which is equal to substantially one-half the cross sectional area of the cylindrical portion 5.

20 In Figure 3 I show what I term a mouth piece 7 formed integral with a cylinder 8, and this cylinder is in turn integral with a piston 9. The piston carries a flange 10 that is designed to ride on the inner surface 11 of the cap 3, see Figure 25 1. If desired, the outer periphery of the flange 10 may be provided with a packing ring, not shown, to prevent any of the tube contents from passing between the flange and the wall 11.

The mouth piece and piston are inserted in the 30 cap 3 and the cylinder or sleeve 8 is slidably received in the cylindrical portion 5. Figure 3 clearly shows the mouth 7 being formed by cutting downwardly from the closed top of the sleeve 8 for providing an edge 12 that lies in a plane 35 that extends diametrically across the sleeve 8. The sleeve is also cut at 13 and this cut extends at right angles to the edge 12.

Before the sleeve 8 is inserted in the cylindrical portion 5 a coiled spring 14 is mounted thereon 40 and when the device is mounted in the cap the spring will bear against the lower edge 15 of the cylindrical portion 5, and will also bear on the upper surface 16 of the piston 9. The spring 14 will yieldingly hold the piston in a position where 45 the flange 10 will abut the top of the neck 2. When the piston is in this position the inclined wall 17 of the mouth 7 will cooperate with the conical end 4 of the cap, and will close the opening 6.

50 From the foregoing description of the various parts of the device, the operation thereof may be readily understood.

In operating the device, the tube 1 is squeezed and this will force the material in the tube up 55.

against the interior of the piston 10, and the material will also be forced into the sleeve 8. Continued pressure on the tube 1 will cause the material to exert sufficient force against the surface 18 of the piston to move the piston upwardly and collapse the spring 14. The cylindrical portion 5 has a wall 19 which will limit further outward movement of the mouth 7 when the edge 13 abuts this wall, see Figure 2. However, when the edge 13 does abut the wall 19 the mouth 7 projects a sufficient distance beyond the opening 6 to permit a ribbon-like form of material to be forced from the tube and through the mouth. The operator in spreading the material on a tooth brush 15 for example holds the tube 1 in a position to cause the inclined surface 17 to ride over the top of the bristles. A continuous pressure on the tube 1 during this movement will cause a uniform flow of material to issue from the mouth 7 and the 20 ribbon form will lie flat on the brush. When the pressure is relieved on the tube 1, the spring 14 will instantly move the piston and close the mouth 7. The device is now ready for further use.

I provide means for locking the mouth and 25 piston against movement during the transportation of the device from the manufacturer to the purchaser. In Figure 1 I show a wire 20 passing through an opening 21 in the cap 3 and abutting the surface 16. This wire is provided with a 30 hand grip portion 22, and then the wire extends along the cylindrical wall of the cap 3. A groove 23 is formed in the top of the cylindrical portion of the cap, and the wire extends along this groove, and is prevented from swinging around the cap. 35 The top of the wire 24 is bent over the pointed end of the cap 3 and engages with the outer edge of the inclined wall 17. It will therefore be seen that the wire 20 engages with the piston 9 and also with the mouth 7 to lock the tube against 40 movement in the cap. The operator before using the device removes the wire by grasping the hand grip portion 22. The device will now function in the manner indicated.

In Figures 4 and 5 I show a modified form of 45 the invention. The flange 10 is done away with in this form of the device and the cylindrical portion or sleeve 8 has its lower end provided with a piston 25. The cap 26 in this form of the device is integral with the tube 27 and a depression 28 is 50 formed in the wall of the cap and causes a projection 29 to extend inwardly from the inner wall of the cap. This projection limits the downward movement of the piston 25. The inner surface of the inclined wall 17 of the mouth 7 is provided 55 with stepped portions 30 instead of with the inclined surface as shown in the form of the device illustrated in Figure 1. The other parts of the device are similar to the parts shown in Figure 1, and therefore like reference numerals will be applied.

The operation of this form of the device is similar to the operation of the form shown in Figure 1. The material in the tube 27 will press against the under surface of the piston 25 and will force the 65 piston upwardly against the spring 14. This movement will be aided by some of the material striking the stepped portions 30 and since these portions extend parallel with the bottom of the piston 25 the material will have a tendency to 70 move the mouth 7 in a direction paralleling the axis of the tube. In the form of the device shown in Figure 1 the inclined inner surface of the wall 17 will cause the material forced against the surface to tend to move the mouth 7 at a slight angle 75 with respect to the tube axis. The form of the

device shown in Figure 4 will therefore no doubt operate more readily than that shown in Figure 1.

The locking means in this form of the device consists of a wire 31 formed into a spring ring, 5 see Figure 5. This wire has an inwardly extending end 32 and a hand gripping portion 33. The end 32 is inserted through an opening 34 in the cap wall 26 and this end passes through a registering opening 35 in the piston 25. The circular portion of the wire surrounds the neck of the cap 10 and the hand grip portion 33 projects a sufficient distance away from the outer wall of the cap to permit a ready grasping of the wire.

It will be seen from this construction that the piston is locked against movement by the wire, 15 and therefore the mouth 7 cannot accidentally open until the wire is removed. The wire can be readily removed by grasping the hand grip portion 33, and then pulling the wire from the cap so as to remove the end 32 from the registering 20 openings 34 and 35. Since the material being forced from the form of the device shown in Figure 4 will act in the same manner as that forced from the other form of the device, further description need not be given.

While I have shown only the preferred forms 25 of my invention, it should be understood that various changes or modifications may be made within the scope of the appended claims without departing from the spirit of the invention.

It is obvious that the top of the cap can be also V-shaped and partially conical if desired.

I claim:

1. In a device of the type described, a cap for a 35 collapsible tube, said cap having a substantially conical-shaped end with an opening extending from the apex and being entirely disposed on one side of a diametrical line extending across the end, and a hollow mouth piece slidable in the cap and being movable through the opening 40 when expelling the tube contents, said mouth piece having an end that will close the opening and lie flush with the remaining surface of the cap when the cap is in closed position.

2. In a device of the type described, a cap for a 45 collapsible tube and having a centrally disposed cylinder, said cap having an opening communicating with only a portion of the cylinder, the portion of the cap closing the other part of the cylinder acting as a stop, a mouth piece slidable 50 in the cylinder and having a portion slidable through the opening, said stop limiting the movement of the mouth piece into open position.

3. In combination, a cap having an opening 55 therein spaced to one side of the center, a piston slidable in the cap and carrying a mouth piece slidable through the opening, said mouth piece carrying an abutment designed to contact with the cap for limiting the movement of the mouth piece into open position.

4. In combination, a collapsible tube, a cap closing the outlet end of the tube and having an outlet opening, a piston slidable in the cap, a mouth piece carried by the piston and being slidable in the opening and normally closing it, and means 65 for locking said piston against movement for sealing the tube contents against leakage, said means comprising a wire extending through the wall of the cap and engaging with the piston, said wire also engaging with the end of the mouth for holding it in closed position.

5. In combination, a collapsible tube, a cap closing the outlet end of the tube and having an outlet opening, a hollow piston slidable in the cap, a hollow mouth piece communicating with the 75

hollow piston and being slidable in the cap opening, said mouth piece being slidable through the cap opening when discharging the tube contents, and spring means for retracting the piston for 5 yieldingly holding the mouth piece in a position where it will close the cap opening, said piston moving against the pressure of the spring means when the tube is squeezed and projecting the mouth piece through the cap opening for expelling the tube contents, said spring means returning the mouth piece to closed position when the pressure on the tube is released.

6. In a device of the type described, a cap having a conical-shaped end with an inwardly extending cylindrical portion carried by the end, said cap having an opening communicating with the cylindrical portion and of less area than the cross sectional area of the cylindrical portion, a hollow piston slidable in the cap, a sleeve communicating with the hollow piston and being slid able in the cylindrical portion, said sleeve having a mouth piece slidable in the cap opening, said mouth piece having an inclined wall acting as a closure for the cap opening when the mouth 25 piece is in closed position, and spring means for yieldingly moving the piston for holding the mouth piece closed.

7. In combination, a cap having a conical-shaped end and a cylindrical portion extending 30 inwardly from the closed end, a hollow piston slidable in the cap, a sleeve carried by the piston and being slidable in the cylindrical portion, said cap having an opening communicating with the cylindrical portion but being of less area than the cross sectional area of the latter, the outer end 35 of the sleeve being formed into a mouth piece and being slidable in the cap opening, the mouth piece having an inclined outer surface normally closing the cap opening and lying flush with the conical portion of the cap, said sleeve having a shoulder abutting the inner surface of the cap when the piston is moved into operative position, 40 conical portion of the cap, said sleeve having a shoulder abutting the inner surface of the cap when the piston is moved into operative position,

said piston when in this position projecting the mouth piece beyond the cap opening.

8. In combination, a cap having a conical-shaped end and a cylindrical portion extending inwardly from the closed end, a hollow piston 5 slidable in the cap, a sleeve carried by the piston and being slidable in the cylindrical portion, said cap having an opening communicating with the cylindrical portion but being of less area than the cross sectional area of the latter, the outer end 10 of the sleeve being formed into a mouth piece and being slidable in the cap opening, the mouth piece having an inclined outer surface normally closing the cap opening and lying flush with the conical portion of the cap, said sleeve having a 15 shoulder abutting the inner surface of the cap when the piston is moved into operative position, said piston when in this position projecting the mouth piece beyond the cap opening, a portion 20 of the inner surface of the mouth piece being stepped.

9. In combination, a cap having a conical-shaped end and a cylindrical portion extending inwardly from the closed end, a hollow piston 25 slidable in the cap, a sleeve carried by the piston and being slidable in the cylindrical portion, said cap having an opening communicating with the cylindrical portion but being of less area than the cross sectional area of the latter, the outer end 30 of the sleeve being formed into a mouth piece and being slidable in the cap opening, the mouth piece having an inclined outer surface normally closing the cap opening and lying flush with the conical portion of the cap, said sleeve having a shoulder abutting the inner surface of the cap 35 when the piston is moved into operative position, said piston when in this position projecting the mouth piece beyond the cap opening, and a split wire ring extending around the cap and having an end extending through the cap wall and en- 40 gaging with the piston to hold it against moving.

GASTON L. LATEUR.
